METHOD AND APPARATUS FOR FEEDING BLANKS

Helmer Anderson, Minneapolis, Minn., assignor
to General Mills, Inc., a corporation of Delaware

Application January 23, 1948, Serial No. 4,013

16 Claims. (Cl. 271—35)

1

This invention relates to a method and apparatus for feeding blanks and is more particularly concerned with the feeding of blanks which are slotted in such a manner as to provide flaps when the blank has been folded into the shape of a carton.

Many devices have been employed in the past to feed such blanks one at a time from one side of a stack, i. e., from the top or from the bottom of said stack. In most cases such feeding is a simple matter because it takes place in a direction parallel to the slots. However, in certain cases it may be desirable to feed the blanks from the stack in a direction at a substantial angle to the slots and in such a case there is a definite probability that the flap portions of the blank being fed will become interlocked with flap portions of an adjacent blank so that either a plurality of blanks will be fed instead of the desired single blank or the flaps will be bent or torn.

With these disadvantages of the prior art in view, it is accordingly one object of the present invention to provide an improved method of feeding such blanks.

It is a further object to provide a method in which blanks may be fed one at a time from one side of a stack in a direction substantially perpendicular to the line of the slots in such a blank.

It is another object to provide a method of feeding slotted blanks in which interlocking engagement of the flaps of the blank being fed with flaps of the adjacent blank is positively prevented.

Still another object of the invention is the provision of apparatus to perform this improved process.

A further object is to provide a device which will feed blanks one at a time from the bottom of a stack in a direction perpendicular to the slots in the blank and which shall include means for producing relative displacement between the portions of the blank being fed at the rear edge of each slot of the blank and the corresponding portions of the adjacent blank at the forward edge of each such slot.

Other objects and advantages will be apparent from the following specification in which a preferred embodiment of the invention has been described with particular reference to the attached drawings forming a part of this application.

In the drawings wherein like reference characters indicate like parts,

Figure 1 is a perspective view of a feeding apparatus embodying the present invention, certain of the parts being omitted for clearness.

Fig. 2 is a schematic perspective view showing how the apparatus performs the process of this invention.

Fig. 3 is a side elevation of the device of Fig.

1, with certain portions broken away to show details of the operating mechanism.

Fig. 4 is an enlarged view similar to Fig. 3 of one of the devices for achieving relative displacement of the carton flaps.

Fig. 5 is an end view of the device of Fig. 1, certain portions being broken away and other portions being omitted for clearness.

Fig. 6 is an enlarged view showing details of a flap-deforming member, said member being shown in its inoperative position.

Fig. 7 is a view similar to Fig. 6 taken on the line 7—7 of Fig. 4, with the blank deforming member in its operative position.

Fig. 8 is a partial sectional view on the line 8—8 of Fig. 1, and

Fig. 9 is a partial perspective view of one of the positioning, supporting, and guide members for the stack of carton blanks.

General description of the method

In order to facilitate the understanding of the detailed description of the apparatus, reference is made to Fig. 2, in which a schematic showing is given of one manner in which the invention may be carried out. As shown in this figure, the invention relates to the feeding of a slotted blank 75. For convenience a blank suitable for use as a box or carton has been shown. Such a blank includes cut or score lines 76 which effectively divide the blank into four body portions each with a corresponding top or bottom flap at each end. Two of the alternate body portions 77 may have a smaller cross sectional area than the other two alternate body sections 78 in order that portions 77 may serve as the ends and portions 78 as the sides of a rectangular carton, when properly folded. Slots 79 serve to divide the edges of the blank into suitable top and bottom flaps 80, 81, 82, and 83 as shown in the drawing.

It will be apparent that if a plurality of such blanks be arranged in a stack and if an attempt is made to feed the bottom-most blank from the stack in the direction of the arrow A in Fig. 2, there will be a strong probability that some of the rearward flaps such as 81, 82, or 83 of the bottom blank might become interlocked with the adjacent forward flaps of the next blank in the stack. As a result of such engagement both blanks might be fed from the bottom of the pile and the various flap portions might become damaged.

According to the present invention suitable supports 43 are positioned underneath the rear edge of each of the flap portions of the bottom blank. Supports 43 have upwardly curved guide portions 44 which project into the slots between the flaps and serve to prevent inter-engagement of the flaps during the feeding movement. In other words, the forward edge of each flap 81, 82,

and 83 of the bottom blank will be guided beneath portions 44 and supports 43 as the blank is fed from the stack and thus any engagement of the forward portions of such flaps with the adjacent flaps of the next blank in the stack will be positively prevented since said flap portions of the next upper blank will be held above the supports 43.

To assist the action of guides 44, suitable flap deforming members or fingers 85 may be mounted in such a manner as to push the forward portions of flaps 81, 82, and 83 downwardly or in a direction on the opposite side of supports 43 from the remaining blanks in the stack. Thus these forward portions of flaps 81, 82, and 83 will be so positioned that they will readily slide beneath guides 44 and supports 43 to prevent interlocking of the flaps as desired. Thus the process of the present invention embodies broadly the idea of feeding the end blank of a stack in a direction substantially perpendicular to the slots in the blank, while simultaneously the flap portions of the end blank are guided along a path which is laterally separated from the flap portions of the adjacent blank in the stack.

The details of one apparatus by which the method of this invention may be performed will now be described.

The supporting frame of the apparatus

With particular reference to Figs. 1 and 3, the apparatus of the invention involves suitable side frame members 11 and 12. These side frame members are joined at the top by cross bars 14, 15, 16, and 17, which cross bars also support certain other portions of the device. For example, at the central portion of the machine on cross bars 14 and 15 are mounted two longitudinal supports 18 and 19 which serve to carry the weight of the central portion of the stack of blanks to be fed. These members are spaced apart as indicated at 21 for a purpose to be described. At the forward end of the machine on cross bars 16 and 17 a further supporting plate 22 is provided. The rear end of support 22 is beveled as shown at 23. The forward portion of plate 22 slopes upwardly, as at 24, to a horizontal feeding platform or support 25. Above portion 25 is a vertical end plate 26 which serves as a positioning means for one end of the stack of blanks to be fed.

The lower edge of plate 26 is somewhat convex as shown with the central portion 27 of the lower edge extending downwardly farther than the adjacent lateral portions 28. The spacing between edge 27 and plate 25 is just sufficient to permit the passage of a single blank when said blank is fed from the stack. The additional spacing between the lateral portions 28 of end plate 26 and the bed plate 25 is desirable in order to permit ready passage of the top and bottom flaps of the blank.

End plate 26 is mounted on vertical supports 29 which in turn are carried by the inner members of longitudinal auxiliary frame members 31. There are two of these longitudinal frame members 31 at each side of the machine and they are angular in cross section (as shown in Fig. 8) in order that they may serve as guides and supports for some of the mechanism described below. The ends of frame members 31 are suitably joined by cross pieces 32 and these frame members are further provided with horizontal plates 33 fastened by bolts 34 to cross bars 14 and 16 respectively.

As shown in Fig. 1, plates 33 each have a rearwardly extending arm 35 which serves as a support for a rear cross bar 36 on which certain portions of the operating mechanism are mounted.

Additional longitudinal supporting bars 37 are mounted on cross bars 14 and 15 and these longitudinal bars serve to carry the supporting plates 38 which cooperate with central longitudinal supports 18 and 19 to carry the weight of the stack of blanks. Plates 38 may be adjusted longitudinally of supports 37 in order that they may be positioned at the rear end of the blanks and may assist in supporting the rear end of the stack squarely so that the bottom blank may be fed from the stack by a suitable pusher.

Blank supporting and guiding means

In order to hold the sides of the stack of blanks in place, vertical supporting and guide members designated generally as 39 have been provided. Members 39, as shown in detail in Fig. 9, include an outwardly tapered upper portion 41 and a vertical lower portion 42. Said guides 39 are adapted to be positioned so that the horizontal distance between the vertical portions 42 will just accommodate the width of the blanks being fed. The outwardly tapered upper portions 41 will thus act as guides to facilitate the positioning of additional blanks on the top of the stack.

At the bottom of guides 39 there are horizontal supporting portions 43 which are adapted to be positioned beneath the flaps of the bottom blank, with one of said supporting portions at the rear edge of each flap of said blank. Supporting portions 43 are provided with the curved guides 44 which extend vertically upward into the slots of the bottom blanks in the stack between adjacent flaps of said blanks, as previously described in connection with Fig. 2.

In order that the vertical position of supports 43 may be adjusted guides 39 are provided with bolts 45 which engage in slots 46 in the vertical supporting arms 47 of suitable bracket members 48.

By proper adjustment of the height of these supports 43 it is possible to have them carry a suitable proportion of the weight of the entire stack of blanks, so that the stack will not rest too heavily on central supports 18 and 19 and will lie flat across said central supports without sagging or arching.

The lower horizontal portions of supporting brackets 48 are adjustably mounted on the longitudinal auxiliary frame members 41 as shown in Fig. 8. With reference to this figure, horizontal portions 48 of the supports are tightly engaged between lower and upper clamp members 49 and 52 respectively, which are connected together by bolts 53. The bottom clamp member 49 may have a portion of reduced cross section as at 51 adapted to fit the space between auxiliary frame members 31 in order to maintain the plate 49 in proper alignment and guide it for movement longitudinally of the machine. It will be apparent from Figs. 1, 8, and 9 that the support and guide members 43 and 44 may be adjusted vertically, laterally, and longitudinally of the machine in order to accommodate themselves to different sizes of the carton blanks and to different spacings of the slots in such blanks. This ready adjustability of the apparatus forms an important part of the present invention.

Blank feeding mechanism

In order to feed the bottom blanks successively from the stack, the following mechanism has been

provided. A suitable pusher 55 is mounted so as to be carried longitudinally forward along the top of supporting members 18 and 19. This pusher 55 is formed as a flat plate or bar, the thickness of which corresponds to the thickness of the particular blank being fed. Thus, as the bar is pushed forwardly, its edge will engage the rear edge of the bottom blank of the stack and will push said blank forward between the end plate 26 and supporting platform 25 without movement of the next or adjacent blank in the stack.

The pusher 55 is carried by parallel chains 56 and is fastened to said chains by suitable brackets 57 (Fig. 5) which may be interlockingly engaged with links of the respective chains. In order to hold the pusher 55 close to the supports 18 and 19 and thus make sure that the pusher engages only the bottom blank, said pusher is provided with a downwardly-extending projection of inverted T-shaped cross section, the narrow portion of which is adapted to fit the space 21 between supports 18 and 19. The two lateral arms of extensions of the portion of T-shaped cross section engage beneath supports 18 and 19 and thus the pusher is maintained in proper alignment crosswise of the guides 18 and 19 and is also held downwardly against the top of said guides as desired, during the feeding movement.

It will also be apparent that the arrangement of pusher 55 and guides 18 and 19 is such that the pusher will move in a straight horizontal line along the top of the supports and will not be permitted to sag with the chains as would normally be the case if supports 18 and 19 were omitted.

Chains 56 are carried at their rear ends on idler sprockets 59 which in turn are mounted on a shaft 61. Shaft 61 extends crosswise of the main frame of the machine and is journaled in bearings 62 which may be adjusted longitudinally of the machine by suitable adjusting screws as shown at 63 (Figs. 1 and 3). This adjustment is desirable in order to avoid unnecessary slack in the chains.

The forward ends of chains 56 are carried on driving sprockets 64 which are suitably keyed to a drive shaft 65. Another driving sprocket 66 is keyed to said shaft and is driven in turn by chain 67 from a suitable sprocket (not shown) on main shaft 68. This main shaft 68 is rotated by a belt 71 which engages pulley 69 of the shaft and is driven by an electric motor 72 or other suitable source of power.

Thus, it will be apparent that in response to the driving action of motor 72, the driving sprockets 64 will be rotated in the direction shown by the arrow in Fig. 3 and will cause corresponding movement of chains 56 and pusher 55. As pusher 55 engages the rear edge of the bottom-most blank, it will push said blank forwardly (i. e. to the left in Fig. 3) between the bottom edge 27 of plate 26 and horizontal guiding and supporting surface 25. After the front edge of the blank passes a suitable distance beyond the end plate 26, it may be engaged by suitable feed rollers 73 and 74 of any desired type which will pull the rest of the blank away from the stack and thus make it unnecessary for chains 56 to extend throughout the entire length of said stack. In other words, pusher 55 starts the blank from the stack and feed rollers 73 and 74, which may be driven in any desired manner, complete the removal of said blank.

While I have shown a continuously operating driving mechanism with only one pusher 55 on chains 56, it will be obvious that this construction could be varied in a number of ways. For example, an intermittent drive which utilizes a standard one-revolution clutch might be employed if desired. Similarly, additional pushers 55 might be positioned on chain 56 so that more than one blank could be fed successively from the bottom of the stack with each complete revolution of the chain whether such motion of the chain be continuous or intermittent. Since such variations of the driving and feeding mechanism are well understood in the art, no detailed description of each such modification need be given.

Flap deforming mechanism

With the blank feeder as described up to this point, it will be apparent that sheets are fed successively from the bottom of the stack, as shown particularly in Figs. 2 and 3 and as described in the earlier portion of this specification. The rear portion of each flap of the bottom blank is carried on a suitable support 43 which is provided with the upwardly curved guide portion 44. These guide portions maintain the forward edge of each of the rear flaps of the bottom blank downwardly displaced with respect to the rear edge of each adjacent forward flap as the bottom blank is fed from the stack. This relative displacement is maintained during the feeding movement and thus the danger of interlocking engagement between the flaps of the bottom blank and the flaps of the adjacent blanks in the stack is avoided.

With certain types of material and suitable vertical adjustment of supports 43, the blanks may be held with the portions ahead of the slots raised in such a manner that the unsupported flap portions at the rear of each slot will sag below the plane of the supports and can thus be fed forwardly without interlocking against the adjacent blank. It is also possible to feed certain blanks according to the invention even though the material does not sag as above described. In this case the guide portion 44 which extends into the slot will serve as a deflector to bend or cam the flap portion in rear of the slot to a downwardly displaced position which will avoid interlock. The guide portion 44 merges smoothly with the horizontal supporting surface 43 and thus this member acts as a deflector and separator, one face of which (e. g. the upper face) engages the stack ahead of the slot, and another face of which (e. g. the opposite face) engages the flap of the bottom blank behind the slot to guide said flap along a path relatively displaced with respect to the bottom or end of the stack. The guides could function in this manner in any stack, whether the blanks are horizontal or vertical.

In a preferred form of the invention, additional means are provided to insure the relative displacement of these bottom flap portions during feeding. Such means may take various forms, and by way of illustration I have shown one such flap deforming mechanism which will now be described.

To assist the relative displacement of the forward edges of flaps 81, 82, and 83 flap deforming members or fingers 85 (shown schematically in Fig. 2) have been provided. The action of these flap deforming members 85 and the details of their construction and mounting are best shown

in Figs. 4, 6, and 7. Thus, in Fig. 4, which is an enlarged view showing the action of the finger 85 which depresses the forward ends of the rear-most flaps 83 of the blanks 75, the member 85 engages the lower group of flaps 83 and depresses them below the level of guide 44 and support 43. Thus, it will be a simple matter for the bottom blank to be fed forward (i. e., to the left in Fig. 4) with absolutely no possibility of inter-engagement of its flaps 83 with the adjacent flaps 82 of the other blanks in the stack.

While it would be theoretically possible to mount the fingers 85 so that they would deflect only the bottom blank; I have found in practice that such an adjustment might result in failure to deflect the flaps in case the thickness of a given blank varied from the thickness for which the machine was set. Therefore I prefer to adjust the fingers 85 so that they engage and bend a number of the bottom blanks as shown. Thus even though specific blanks vary in thickness, the bottom blank will always be deflected.

As shown in Figs. 6 and 7, each member 85 is pivoted at 86 to a bifurcated crank arm 87. Members 85 are similarly pivoted at 88 to another forked crank or lever 89. Pivot 86 is at the upper end of a member 85 as shown, while pivot 88 is spaced at an intermediate point on said member.

Crank arm 87 is integrally connected to a hub or bearing portion 91 which is pivotally supported by shaft 92 which extends lengthwise of the machine. Bearing portion 91 is freely rotatable on shaft 92 so that crank arm 87 may move through the desired arc without movement of shaft 92.

The forked crank arm 89 is likewise integrally connected to a bearing or hub portion 93 which is mounted on another longitudinal shaft 94. In order that lever 89 may be firmly connected to shaft 94 and may be driven thereby the bearing portion 93 is of split construction as shown at 95, the two portions of the bearing being clamped together by a bolt 96 so that the bearing portion is firmly connected to shaft 94. Thus when shaft 94 is rotated back and forth or oscillated by mechanism described below, lever arm 89 will be similarly moved and will cause up and down movement of deforming finger 85. By loosening bolts 95 the position of fingers 85 may be adjusted longitudinally and vertically, in order to correspond to the various adjusted positions of supports 39.

It should be noted that the lever 89 is longer than lever arm 87. Because of this difference in length, there will be a tendency for the lower end of member 85 to be pushed inwardly against the stack of carton blanks as said member is moved downwardly from the position of Fig. 6 to the position of Fig. 7. Thus a compound movement of flap deforming members 85 is obtained which is particularly advantageous for the purpose at hand.

Longitudinal shafts 92 and 94 are supported by suitable bearing portions 97 and 98 on supporting brackets 99. These brackets 99 have horizontal base portions 101 which are adjustably mounted on the top of the machine as shown in Fig. 1.

With reference to that figure, it will be noted that there are three of the horizontal bearing brackets 101, two of which are adjustably clamped on the longitudinal auxiliary frame members 31 by means of clamping plates 104 and clamping bolts 103 which pass through slots 102

in brackets 101 and engage the plates 104. Plates 104 are substantially similar in cross section to plates 49 shown in Fig. 8 and are further provided with upwardly extending flanges which form a channel to maintain the bracket portions 101 in alignment crosswise of the frame members 31. By loosening bolts 103, it will be clear that the supporting brackets may be adjusted both laterally and longitudinally of the machine. These adjustments correspond to the similar adjustments of members 39 and in combination with the adjustments of fingers 85 and bearings 93, this makes it possible for the mechanism to be adapted to blanks of various width and blanks in which the slots are positioned at different longitudinal points.

The third bearing portion 101 for the rear end of driving shaft 94 is identical with the other similarly numbered brackets but is positioned in a channel 105 of rear cross piece 36. A bolt 106 and clamping washer 107 are utilized to clamp this end bearing in the desired position. This bearing is adjustable laterally in the same manner as the others but it is unnecessary to provide for longitudinal adjustment of this particular member.

Since shaft 92 serves merely as a bearing for the upper crank arms 87, it need not be free to rotate and is preferably clamped in the bearing bracket 99. Shafts 94, on the other hand, serve as the driving means to oscillate the links 89 and members 85 and therefore shafts 94 are mounted for free rotation in supporting brackets 99.

With reference again to Figs. 6 and 7, the lower ends of flap deforming members 85 are notched as shown. These notches are formed by a cut-back portion 108 which extends in a substantially vertical direction and an adjacent cut back portion 109 which is sloped as shown. Thus a hook is provided at the lower end of the member 85, the tip 111 of said hook being substantially parallel to the direction of movement of member 85. The lower portion 112 of the member is slightly convex for engagement with the flaps 83. In the upper or retracted position of the deforming members 85, as shown in Fig. 6, the lower ends of the members are clear of the stack of carton blanks. As the shaft 94 is rotated in a clockwise direction, these fingers 85 will be forced downwardly and inwardly against the stack and will engage the flaps of the lower blanks in the stack at a point just behind the slots in the blank, i. e., at the forward edge of the flaps, with reference to the direction of feed of the blank. The notched portion of fingers 85 will accommodate those flaps of the upper blanks which are not depressed by the end 112 of the finger.

It will be remembered that the flaps 82 just ahead of the slot in question are supported on members 43 and are thus incapable of downward movement with flaps 83. Thus a relative displacement is obtained between the forward edges of flaps 83 and the rearward edges of flaps 82 which permits the bottom carton of the stack to be fed forwardly with no possibility of interlocking engagement between flaps 83 of the bottom blank and flaps 82 of the next to the bottom blank.

Driving mechanism for flap-deforming members

In order to drive the shafts 94 I have provided crank arms 113 at the rear end of each shaft as shown in Figs. 1, 3, and 5. These crank arms

113 are pivoted at 114 to connecting links 115. Each connecting link 115 has an adjustable nut or turnbuckle portion 116 adapted to engage the upper threaded end 117 of a suitable connecting rod 118.

The lower ends of connecting rods 118 are connected by pivot pins 119 to universal links 121 (Fig. 3) which are further connected by pivot pins 122 to crank arms 123. Since the axes of pins 119 and 122 are at right angles to each other, it will be apparent that the linkage will adapt itself readily to the various lateral positions in which shaft 94 may be adjusted.

Crank arms 123 each have split hub or bearing portions 124 which may be clamped together by bolts 125 so that crank arms 123 are firmly connected to a shaft 126 suitably supported crosswise of the machine frame. Shaft 126 has a further lever or crank arm 127 extending in a direction substantially opposite to that of cranks 123. Said lever arm 127 is connected to one end of a suitable return spring 128, the other end of which is fastened to a portion 129 of the main frame. Spring 128 tends to urge shaft 126 in a counter clockwise direction in Fig. 3 and thus urges connecting rods 118 upwardly to rotate shafts 94 so that the flap deforming fingers 85 are urged in turn to their upper or retracted position as in Fig. 6.

To rotate shaft 126 in the opposite, or clockwise direction, a further crank arm 131 is provided, the lower end of said crank arm being pivoted at 132 to the adjustable end 133 of a longitudinal drive rod 134. The other end 135 of this drive rod is pivoted at 136 to the bottom of a supporting lever 137, the upper end of said lever being pivoted at 138 to one of the frame members 139. This supporting lever 137 carries a rotatable cam follower 141 which engages the periphery of a cam 142 on main drive shaft 68. As shown in Fig. 3 cam 142 is divided into two portions, one of greater radius as at 143 and the other of smaller radius as at 144. Cam follower 141 is urged constantly against the periphery of cam 142 by the action of spring 128 on crank 127 and shaft 126. Thus as drive shaft 68 is rotated, the cam follower 141 will be forced to the left in Fig. 3 by the larger portion 143 of the cam 142 and will thus rotate shaft 126 in a direction which will cause fingers 85 to be depressed to the position of Figs. 3, 4, 5, and 7.

When the portion 144 of shorter radius reaches a point opposite cam follower 141 the various shafts and links will be moved by the action of spring 128 so that the fingers 85 return to the position of Fig. 6. Cam 142 is so oriented with reference to drive shaft 68 and the position of pusher 55 on chains 56 that the forward portions of the carton flaps will be displaced downwardly just before the pusher 55 engages the lowermost blank, and these flaps will be held in their downwardly displaced position until the feeding of the bottommost blank is substantially complete, so that there is no further possibility of interlocking engagement of any of the flaps.

In the particular mechanism shown the gearing is such that main drive shaft 68 will rotate more than once for each complete revolution of chains 56. It is contemplated that there will be a corresponding number of pushers 55 equally spaced around the chains. For simplicity, only one of the pushers 55 has been shown, and it will be clear that the particular number of pushers and the gear ratio employed will be a mere matter of choice for a skilled worker in this field.

In order that the carton blanks in the stack may be held firmly in position and flattened against the supporting surface so that the pushers 55 will engage the bottom blank squarely and will not engage any of the adjacent blanks, a suitable weight member 145 has been provided. This weight is carried at the end of a lever arm 146 which in turn is carried by a bearing portion 147 pivoted at 148 to vertical supporting brackets 149 on rear cross piece 36.

From the foregoing description it will be apparent that a device has been provided by which the method of this invention can be carried out and that this apparatus involves many advantages and improvements which combine to achieve the desired result and provide for efficient feeding of slotted blanks. As explained in the foregoing description the blank feeding mechanism is fully adjustable so that it may accommodate carton blanks of various widths and lengths, and blanks which have different spacings between the slots which separate the top and bottom flaps. Furthermore, the invention is not necessarily limited to the feeding of blanks from the bottom of a stack, although this form is preferred because of the ease of replenishing the stack and because most carton folding machines are designed to receive blanks in a horizontal plane. Since many obvious changes may be made in the specific details of construction of the machine by persons skilled in this field, it is my intention that this invention shall include all such modifications falling within the scope and spirit of the attached claims.

35 Now, therefore, I claim:

1. The method of feeding slotted blanks laterally from one end of a vertical stack of superimposed horizontally extending blanks in which the slots extend transversely of the direction of feed, which comprises causing relative vertical displacement of the portions at the rear edge of each slot of a plurality of the end blanks and the corresponding portions at the forward edge of each slot of the adjacent blanks, and maintaining the relative vertical displacement of said plurality of blanks while feeding only the end blank from the stack.

2. The method of feeding slotted blanks from one end of a stack in which the slots extend transversely of the direction of feed, which comprises supporting the portions of the end blank at the forward edge of each slot, separately deforming a portion of the end blank at the rear edge of each slot in a direction to clear the forward edge portions of slots of the adjacent blank, and thereafter feeding said blank from the stack while maintaining said portions in deformed position until they have cleared the slot edges of adjacent blanks.

3. The method of feeding slotted blanks from one end of a stack in which the slots extend transversely of the direction of feed, which comprises holding a portion of the end blank at the forward edge of each slot to prevent lateral displacement of said forward edge portion, separately deforming a portion of said blank at the rear edge of each slot in a direction to clear the forward edge portions of the adjacent blanks while the blanks are otherwise stationary, and then feeding said end blank from the stack and maintaining said portions in deformed position until they have cleared the slot edges of adjacent blanks.

4. The method of feeding slotted blanks from one end of a stack in which the slots extend

11

transversely of the direction of feed, which comprises supporting the portions of the blanks at the forward edge of each slot to prevent lateral displacement of said forward edges, separately deforming the portions of a plurality of end blanks at the rear edge of each slot in a direction to clear the forward edge portions of adjacent blanks, and thereafter feeding only the end blank from the stack while maintaining said portions of the remaining blanks in deformed position and thereby guiding the end blank clear of the slots of adjacent blanks.

5. In an apparatus for feeding slotted blanks from one end of a stack in which the slots extend transversely of the direction of feed, the improvement which comprises a support engaging said end of the stack at the forward side of a slot, a flap deforming member, means for moving the member against a portion of at least the end blank at the rear side of said slot and thereby displacing the portion in a direction perpendicular to the plane of the blank and away from the stack to clear said support, and means for feeding said end blank from the stack while said portion is displaced.

6. Apparatus as described in claim 5 in which said support and said deforming member are adjustably mounted both laterally and longitudinally for accommodation of different blank and slot dimensions.

7. In an apparatus for feeding slotted blanks from the bottom of a stack in which the slots extend transversely of the direction of feed, the improvement which comprises a support located under said stack at the forward edge of a slot, a movable deflecting finger engaging at least the bottom blank at the rear edge of said slot and bending said rear edge downwardly below said support prior to feeding movement of the bottom blank, and means for thereafter feeding said bottom blank forwardly from beneath said stack while said edge portion is bent.

8. Apparatus as in claim 7 in which said support and said finger are adjustably mounted both laterally and longitudinally for accommodation of different blank and slot dimensions.

9. In an apparatus for feeding slotted blanks from the bottom of a stack in which the slots extend transversely of the direction of feed, the improvement which comprises vertical deforming members located adjacent said stack at the rear edge of each slot, a pair of shafts extending longitudinally of the machine and disposed one above the other adjacent said members, crank arms on said upper shaft pivotally connected to an upper portion of each deforming member, crank arms on said lower shaft pivoted to a lower portion of each deforming member, means for driving one of said shafts from a first position in which said deforming members are raised and retracted, to a second position in which said members engage and depress at least the bottom blank portions at the rear of each slot, and means for feeding the bottom blank from said stack while said one shaft is in said second position.

10. Apparatus as in claim 9, in which said upper crank arms are shorter than said lower crank arms.

11. Apparatus as in claim 9, in which said shafts are mounted in bearing brackets, said brackets being adjustable transversely of the machine for accommodation of blanks of different width.

12

12. Apparatus as in claim 9, in which said crank arms are mounted for adjustment longitudinally of said shafts for accommodation of blanks having different slot locations.

13. In an apparatus for feeding slotted blanks from the bottom of a stack in which the slots extend transversely of the direction of feed, the improvement which comprises supports located under said stack ahead of each slot, vertical deforming members located adjacent said stack at the rear edge of each slot, a pair of shafts extending longitudinally of the machine and disposed one above the other adjacent said members, crank arms on said upper shaft pivotally connected to an upper portion of each deforming member, crank arms on said lower shaft pivoted to a lower portion of each deforming member, means for driving one of said shafts from a first position in which said deforming members are raised and retracted, to a second position in which said members engage and depress at least the bottom blank portions at the rear of each slot to a level below said supports, and means for feeding the bottom blank from said stack while said one shaft is in said second position.

14. Apparatus as in claim 13, in which said shafts are mounted in bearing brackets, said brackets being adjustable transversely of the machine, and in which said crank arms are mounted for adjustment longitudinally of said shafts, and said supports are adjustable longitudinally, transversely, and vertically, for accommodation of different blanks.

15. In an apparatus for feeding slotted blanks from the bottom of a stack in which the slots extend transversely of the direction of feed, the improvement which comprises deforming members mounted adjacent said stack for movement between a first position in which the members are retracted out of engagement with the stack and a second position in which the members are moved inwardly and downwardly and thereby engage and depress the portions of at least the bottom blank at the rear of each slot, means for moving said members from first to second position, and means for thereafter feeding the bottom blank from the stack.

16. In an apparatus for feeding slotted blanks from the bottom of a stack in which the slots extend transversely of the direction of feed, the improvement which comprises deforming members mounted adjacent said stack for movement between a first position in which the members are retracted out of engagement with the stack and a second position in which the members are moved inwardly and downwardly and thereby engage and depress the portions of a plurality of bottom blanks at the rear of each slot, means for moving said members from first to second position, and means for thereafter feeding the bottom blank from the stack.

HELMER ANDERSON.
